CLAIM

We claim the ornamental design for frame for a seating unit, as shown.

DESCRIPTION

FIG. 1 is a perspective view of a frame for a seating unit embodying the present invention;

FIG. 2 is a front view of the frame for a seating unit shown in FIG. 1;

FIG. 3 is a right side view of the frame for a seating unit shown in FIG. 1, the left side being a mirror image thereof;

FIG. 4 is a rear view of the frame for a seating unit shown in FIG. 1;

FIG. 5 is a top view of the frame for a seating unit shown in FIG. 1; and,

FIG. 6 is a bottom view of the frame for a seating unit shown in FIG. 1.
